UNITED STATES PATENT OFFICE.

GEORGE GORDON VIVIAN, OF DENVER, COLORADO, ASSIGNOR OF ONE-HALF TO LAFAYETTE HANCHETT, OF SALT LAKE CITY, UTAH.

SMEILING-FURNACE.

No. 862,684.

Specification of Letters Patent.

Patented Aug. 6, 1907.

Application filed March 18, 1907. Serial No. 363,068.

To all whom it may concern:

Be it known that I, GEORGE GORDON VIVIAN, a citizen of the United States of America, residing at the city and county of Denver and State of Colorado, have invented a new and useful Smelting-Furnace, of which the following is a specification.

My invention relates to improvements in reverberatory smelting furnaces; and the objects of my invention are: first, to provide a reverberatory smelting furnace capable of continuous work and operating with a high degree of efficiency and economy. Second, to provide an ore smelting furnace in which the matte is adapted to be drawn off at its front end portion, or the end furthest from its fire box, and consequently the coolest portion of the furnace. Third, to provide an ore smelting furnace in which the slag is adapted to be drawn off at its back end portion or the end nearest to its fire box, and consequently the hottest portion of the furnace. Fourth, to provide an ore smelting furnace in which the 10 hearth or slag chamber is provided at its front end portion with angular walls diverging from the central portion of the hearth for a short distance, and with ore feeding chutes in said walls arranged to connect through the side walls of the furnace with a supply of ore preferably through the medium of ore holding and feeding hoppers, and at their lower ends extend through the sides of the walls into or close to the floor surface of the hearth, so as to discharge ore directly in contact with and into the body of molten slag normally resting on the 15 hearth when smelting ore, and so arranged that the ore cannot fall from the ore chutes onto and into the molten ore slag, and that are arranged to feed the ore into the furnace at its front end portion, and into the coolest portion of the hearth chamber and of the body of molten ore thereon. Fifth, to provide an ore smelting furnace in which the ore is fed on the molten ore body in such a manner as to completely eradicate, eliminate, and prevent any possibility of losing any of the ore values by the carrying off by the draft of the products 20 of combustion as it flows from the fire box to the chimney, of the ore dust. Sixth, to provide an ore smelting furnace arranged to smelt ore and to which ore can be fed and the slag withdrawn therefrom without admitting cold air to the hearth chamber, and to the molten ore, and that is constructed without door-controlled openings in its sides and roof through which to feed ore and to withdraw or skim off the slag. And seventh, to provide a simple, easily constructed, thoroughly practical smelting furnace of the reverberatory type, that 25 will extract a matte product from the ore of a higher percentage of metal value, with a larger ore smelting capacity, and with less cost per ton of treatment in labor and fuel than the reverberatory smelting furnaces now in use. I attain these objects by the mechanism illustrated in the accompanying drawings, in which:

Figure 1, is a sectional plan view of a reverberatory furnace embodying my invention. Fig. 2, is a central longitudinal sectional elevation of the same. Fig. 3, is a side elevation of the furnace. Fig. 4, is a cross section of Fig. 3, on line 4—4 of Fig. 3. And Fig. 5, is a rear end view, the ash pit being in section.

Similar letters of reference refer to similar parts throughout the several views.

Referring to the drawings, the numeral 1, designates in general a reverberatory furnace embodying my invention.

2 designates the foundation side walls; 3, the foundation rear end wall; and 4, the foundation front end wall.

5 designates the fire box. This fire box is made narrower in width than the body of the furnace, and is formed in the center of the width of the furnace, and is made of a length sufficient to receive a grate surface of sufficient capacity for the size of the furnace.

6 designates the fire grate; 7 is a coal entrance hopper in the roof of the fire box, and below the grate bars an 75 ash pit 8 is formed.

A hearth 9, which may be constructed of any suitable material and may be arranged in any desired manner, is formed on the foundation walls 2 and 3 and 4, and a fire bridge wall 10, is formed between the fire box and 80 the adjacent end of the furnace. This bridge wall is a vertical extension of the rear end wall above the end of the hearth, and extends beyond the fire box, and with the foundation wall 3 forms the rear end of the furnace. The foundation walls 2 and 3 and 4 extend above the 85 hearth and are integrally formed, and a roof 11 extends integrally from the sides and ends over the hearth, thus forming a molten ore chamber 12 above the hearth.

At the front end of the furnace is a flue 13, connecting with a chimney 14, which extends from one corner of 90 the front end of the furnace.

The several features above enumerated are common to all reverberatory smelting furnaces; and in addition to these features the reverberatory furnaces in use are provided with doors in front and in their sides, through 95 which the slag is skimmed off from the body of melted ore on the hearth, and through which the operation may be watched and repairs made, and ore is sometimes fed through these doors to the hearth. The feeding of the ore however, is most generally done through door-controlled openings in the roof of the furnace, from hoppers positioned above the openings, and the ore is fed in intermittent charges of large quantities, which fall into the molten slag with a splash, which scatters the slag and matte onto the inner surface of the hearth chamber, 105 thus causing an immense amount of dusting, a large volume of which, carrying values, is carried up the chimney. The splashing of the hot slag and matte against the walls of the hearth chamber causes them to be rapidly eaten away and to deteriorate and to shrink 110

or expand and to finally crack from the unequal heat. The slag is drawn off through doors located at the furthest end of the furnace from the fire box, which is the coolest part of the furnace, or through doors in the 5 sides of the furnace, in such a manner that the conditions are unfavorable to the settling of the matte and the skimming off of the slag portion of the melted ore on the hearth, and when doors are used for this purpose, a large volume of cold air is admitted to the furnace, causing 10 a chilling of the slag, which in a measure prevents a proper and free settling of the matte or metal values to the bottom of the slag, and along the bottom of the hearth, and the admittance of cold air to the slag-chamber also causes rapid contraction and expansion and subjects 15 the furnace to severe strains that cause its sides and roof to crack. The matte or liquid metals are drawn off through doors located at the side of the furnace, and this results in a portion of the matte being carried off with the slag, as it is hotter at this point than at the 20 front end of the furnace, and the matte is in a state of greater fluidity and ebullition at this point and mixes more freely with and settles slower than at the front end of the furnace.

My invention, however, contemplates a radically 25 different arrangement of the ore-feeding, slag-tapping and matte-tapping elements of reverberatory smelting furnaces, and a construction that will prevent a loss of values by dusting, by imperfect settling of the matte, and by alternate cooling and heating, which also results 30 in an unnecessary waste in fuel and in time. To accomplish these results, I form the flue 13, which connects with the chimney 14, at or adjacent to the front end of the furnace, and preferably in the center of the width of the furnace and in its roof, and I shape 35 the hearth of the furnace square at the fire box end, and with straight parallel sides to near the front end portion of the furnace, from which point the sides converge into straight angular walls 15, which meet at the center of the front end of the furnace, at which point a metal 40 or matte tap-hole 16 is formed through the front end wall. This tap hole is placed on a level with the bottom of the hearth,—and at the fire-box or rear end wall of the hearth I place one or more slag tap-holes 17, preferably using two and placing them one on each side of 45 the fire-box. These slag tap holes are placed a trifle above the bottom of the hearth so as to drain the upper portion of the body of molten slag lying on the hearth. The roof of the furnace is made solid and without openings of any kind, and the sides of the furnace are also 50 preferably made solid except that two entrance doors 18 are preferably placed in each side wall, which allow the operator to watch the smelting operation and to keep the inside entrances of the slag tap-holes in good order, as they require occasional repairing to prevent their 55 being burned out too large in diameter to properly keep the slag under control. An air chamber 19 is also formed between the side and end foundation walls below the hearth. In the walls 15 of the angled front end portion of the furnace, I form ore feeding chutes 20 in the form of oblong apertures which stand at an outwardly inclined angle from where they enter the furnace. I preferably arrange these feed chutes to extend along the greater portion of the length of these angled walls from the point where they intersect the 60 side walls to near the apex or front end of the furnace 65

where they come together. These oppositely disposed ore feed chutes could be each made in one long narrow aperture or slot, but in order to insure the greatest strength of wall I preferably form two or three or more ore chute apertures, five being illustrated, at a short 70 distance apart, and leave an integral portion of the wall as a partition between them to support and tie the hearth face portion of the wall to the outside portion of the side and end walls. These ore feeding chutes extend down through the angled walls of the furnace, to 75 or close to the floor of the hearth, and in their top entrances I fit the discharging ends of a pair of ore feed hoppers 21 and 22, which are connected by launders 23 with ore storage bins, which I do not illustrate.

Smelting ore consisting of concentrates from jigs and 80 concentrating tables varying from about one-quarter inch mesh down to about a hundred mesh and even finer, make up a large part of the character of size of the ore product usually smelted in reverberatory furnaces, and all kinds of smelting ore that is shipped direct 85 from the mine, which when in large lumps passed through rock breakers and is reduced to small pieces, in which form it is easily fed through the hoppers and chutes to the hearth after being first mixed with proper fluxes when they are required.

As my invention contemplates the automatic and continuous gentle and slow feeding of ore to the furnace without any agitation or movement of the ore that would raise its dust particles into the draft current flowing from the fire box to the chimney, the hoppers 90 are provided with ore enough to keep the feed chutes in the opposite angular walls of the head end of the slag chamber full at all times. These ore chutes are adapted in area to feed and discharge ore continuously onto the molten body of ore on the hearth without allowing 95 it to drop, and the slag tap holes and also the matte tap hole are adapted to be continuously open in all cases where the ore smelts quickly and readily, and it is necessary to feed fast in order not to allow the slag to lie any longer on the hearth than is necessary for it to 100 arrive at the degree of the heat necessary to reduce it to that state of fluidity necessary to allow all of the ore's metallic values to separate from its slag element, and it easily and thoroughly settle out of the slag, and form the lower stratum of the molten ore body along the floor or 105 hearth of the furnace. But when complex or refractory ores are smelted and the feed though continuous is slow, it may not be desirable or necessary to keep the slag and matte tap-holes open all of the time, but it will be sufficient to open them as required at intervals, 110 as is customary. But on ores that contain but little value and a large amount of slag, it might be necessary to keep the slag tap open continuously and draw off the matte at intermittent periods when a sufficient quantity has accumulated. The slow easy continuous 115 flowing feed movement of the ore at the front end of the hearth directly on top of and into the body of molten ore prevents the fine dust particles of the ore from getting into the flame and heat and combustion draft that flows constantly and with considerable 120 force from the fire box to the chimney over the molten ore-slag and thus completely and thoroughly eradicates this particular element of loss of values from the economic value of my furnace. This automatic 125 method of feeding ore directly onto and into the body 130

of molten ore completely eliminates the splashing of the molten slag and matte against the sides of the hearth or slag chamber, and also completely avoids the admittance of cold air into the hearth chamber 5 from the opening of doors, as in the most advanced and perfected type of reverberatory furnaces in use at the present time. The elimination of doored openings into the furnace both for recharging and for withdrawing or discharging or skimming slag from it or for leveling 10 the charge, is a feature of great economic value in the saving effected in the cost of fuel and in the time required to regain the heat lost, as it is easy to maintain an even temperature where no cold air is admitted; and the deleterious action on the molten ore due to frequent chillings, is thus avoided, and the cost of labor and the wear and tear of the furnace greatly reduced, 15 making altogether an item representing a saving of from about ten to twenty-five per cent. in the cost of treatment and higher extraction of values, which when coupled with a large increased capacity of my automatic feed over intermittent manual feeding establishes a far greater degree of utility, practicability, and economic value for my improved automatic feeding 20 reverberatory smelting furnace over all other reverberatory furnaces known to the art of smelting ores.

In order to protect the slag outlet apertures from the intense heat of the interior of the furnace and scouring effect of the molten ore, I place in the walls of the furnace a water jacket which may be of any suitable construction for this purpose, preferably illustrating a water carrying coil of pipe 24, which at one end extends from a supply of cold water and enters the wall adjacent to a tap-hole and extends around the tap-hole and then at its opposite end extends out of the furnace and leads 35 to waste.

The operation of my improved furnace is as follows: The ore is fed into the hoppers from a source of supply, and flows freely into the feed chutes, which are always kept full of ore, and the ore feeds by gravity into the 40 body of molten slag which is always from about one to two or more inches deep on the hearth, and the ore feeds of its own weight through the ore chutes onto and into the body of molten ore moving slowly and gently into it only as fast as it melts, and as the feed 45 chutes are positioned at the front end of the furnace, which is the coolest part of the body of molten slag, it does not disturb or cool the hottest portion of the molten ore, which is at the fire box end or back end of the furnace, and as the ore melts it flows towards the fire box 50 end of the furnace and is heated hotter and hotter, and the metals settle to the bottom of it along the floor portion of the hearth, as matte or metal, which is the collected fluid metals of all kinds in the ore, and this matte flows along under the top stratum of the melted 55 ore which is the slag portion, and consists of the fluid earthy matter in the ore, to the matte tap-hole at the front or feed end of the furnace, while the hot slag is drawn off through the slag tap holes at the fire box end of the furnace, and as the slag at this end of the furnace 60 is in the hottest zone of the furnace, it is of clearer fluidity and consequently the metals of the ore settle out of it more readily and quicker and more thoroughly than out of the cooler portions of the molten ore slag, while the slag is clear and free from the metals or matte

and carries less values away than in furnaces where the 65 slag is drawn off through side doors that admit chilling air to the interior of the hearth chamber; moreover, the flame and products of combustion of the fire box in flowing from the fire box to the chimney flue come in contact with the ore as it flows into the hearth chamber 70 onto the molten ore body, and heats it and thereby aids in melting it and to that extent increases the smelting capacity of the furnace.

Suitable metal launders which I do not illustrate, are arranged below the tap-hole spouts to conduct the slag 75 and matte away from the furnace.

My improved automatic ore feed reverberatory furnace is simple and thoroughly practical, and will enable a higher percentage of the values of ores and a cleaner and purer matte to be obtained and an economic 80 saving to be made over the present reverberatory furnaces used for smelting ores, and at the same time provides a continuous and a more perfect smelting apparatus.

While I have illustrated the preferred construction and arrangement of my improved furnace, I do not wish 85 to be limited to it, as many changes might be made without departing from the spirit of my invention.

Having described my invention, what I claim as new and desire to secure by Letters Patent, is:

1. A reverberatory smelting furnace comprising a hearth, a combustion chamber communicating therewith, a slag tap adjacent said combustion chamber, and a matte or metal tap remote from said combustion chamber. 90
2. A reverberatory smelting furnace comprising a hearth, a combustion chamber adjacent one end of the hearth and communicating therewith, a slag tap adjacent said combustion chamber, and a matte or metal tap opposite said slag tap. 95
3. A reverberatory smelting furnace comprising a hearth, a combustion chamber communicating therewith, a slag tap adjacent said combustion chamber, a matte or metal tap remote from said combustion chamber, and ore-feeding means adjacent said metal tap. 100
4. A reverberatory smelting furnace comprising a hearth, heating means therefor, a slag tap adjacent said heating means, a matte or metal tap remote from said heating means, and ore-feeding means disposed on each side of said metal tap. 105
5. A reverberatory smelting furnace comprising a hearth, heating means therefor, a slag tap adjacent said heating means, a matte or metal tap remote from said heating means, and ore-feeding means adjacent said metal tap and arranged to feed ore in proximity to said hearth. 110
6. A reverberatory smelting furnace comprising a hearth, heating means therefor, slag and matte or metal taps, and means adjacent said matte or metal tap for feeding ore to said furnace in proximity to said hearth. 115
7. A reverberatory smelting furnace comprising a hearth having a converging end, a matte or metal tap adjacent said converging end, and means adjacent said tap for feeding ore to said furnace. 120
8. A reverberatory smelting furnace comprising a hearth having a converging end, a matte or metal tap adjacent said converging end, and means adjacent said tap for feeding ore to said furnace in proximity to said hearth. 125
9. A reverberatory smelting furnace comprising a hearth, heating means therefor, slag and matte or metal taps, and means for feeding ore to said hearth, said ore feeding means comprising a plurality of channels discharging into said furnace in proximity to said hearth. 130
10. An automatic continuous ore feeding reverberatory smelting furnace, comprising an operatively arranged and heated smelting furnace, having a hearth, a plurality of ore feeding chutes arranged at the front end portion of said hearth on opposite sides of said hearth in its side walls, arranged to discharge the ore adjacent said hearth. 135

11. An automatic continuous ore feeding reverberatory smelting furnace, comprising an operatively heated hearth chamber provided with converging angular walls at its front end portion, a continuously feeding ore chute in each 5 of said angular walls, having their discharge ends arranged close to the floor surface of the hearth.
12. An automatic continuous ore feeding reverberatory smelting furnace, comprising an operative smelting hearth, an ore feeding chute in the walls of the front end of the 10 furnace arranged to continuously convey and feed ore directly to the surface of said hearth, a matte tap-hole at the front end of said hearth and furnace, a fire box at the back end of said furnace, and slag tap-holes at the back end of said furnace adjacent to said fire box.
- 15 13. An automatic continuous ore feeding reverberatory smelting furnace, comprising an operative smelting furnace provided with a fire box, and a chimney, and containing a smelting hearth and a hearth chamber, parallel side walls to said chamber, a rectangular end wall at its fire 20 box or back end, and with converging angular walls at its front end that meet together at the central portion of said hearth, a matte tap-hole at the apex of said converging angular side walls in the front end of said furnace level with the floor surface of said hearth, slag tap-holes in the 25 back end wall of said furnace slightly above the floor surface of said hearth, and ore feeding chutes in the opposite converging angular walls of said hearth chamber arranged to continuously convey and feed ore directly into and onto the said body of molten ore on said hearth at the front end 30 portion of said hearth and furnace.
14. In an automatic continuous ore feeding reverberatory smelting furnace, the combination with the hearth, the front, the back, the side walls, and roof, the chimney, and the fire-box of a reverberatory ore smelting furnace, 35 of a hearth chamber having at its front end converging angular side walls arranged to converge from the side walls together and meet in a point at the front end of the hearth, a matte tap-hole at the meeting point of said converging walls through the front wall of said furnace level 40 with the floor surface of said hearth, slag tap-holes at the fire box or back end of said furnace a little above the floor surface of said furnace, and positioned on opposite sides of said fire box, a plurality of ore chutes formed in the opposite side walls of said hearth chamber and extending 45 from the outside of said walls through said walls to close to the floor surface of said hearth, said ore chutes being arranged to feed ore continuously from opposite sides of said furnace into the opposite sides of and at the front end portion of said hearth and furnace, whereby 50 said ore is fed continuously to the coldest portion of said furnace and is fed directly onto and into the body of molten ore on said hearth, and the slag product of said molten ore flowing to and being tapped off at the hottest portion of said hearth and furnace, and the matte flowing 55 to and being tapped off at the front and coldest end of said hearth and furnace, the said positioning of the slag and matte tap-holes permitting the natural order of separation of the slag and matte elements of the molten ore.
15. In an automatic continuous ore feeding reverberatory smelting furnace, the combination with the combustion chamber fire box, of a walled and roofed ore chamber provided with a chimney and connected at one end to the combustion chamber, an ore smelting hearth in said ore chamber, said ore chamber being formed with side walls 60 that converge from its sides to point that forms its terminal front end, an ore feeding chute in each converging wall of said ore chamber arranged to convey ore through
- the walls of said ore chamber to the adjacent edges of said hearth, and means including an ore feeding hopper for feeding ore to said chutes. 70
16. In an automatic continuous ore feeding reverberatory smelting furnace, the combination of the combustion chamber, with the walled inclosed ore chamber and the hearth, said ore chamber being formed with its sides converging at its front end, a plurality of ore feeding chutes 75 extending into each of the converging walls of said ore chamber to close to the surface of said hearth and arranged and adapted to continuously discharge ore directly at and into the adjacent edge surfaces of said hearth, means including a hopper provided with a plurality of ore 80 discharge chutes for feeding ore continuously to said chutes and hearth, means for tapping slag from said hearth at the combustion chamber end of said hearth and ore chamber, and means for tapping matte from the front or coldest end of said ore chamber and hearth adjacent 85 to said ore feeding chutes.
17. In an automatic continuous ore feeding reverberatory smelting furnace, the combination with an operative combustion chamber fire box, of an operatively wall-in- 90 cased ore chamber, a hearth in the bottom of said chamber, a plurality of ore feeding chutes extending through the walled incased ore furnace of said ore chamber to said hearth and adapted to continuously feed ore automatically to said hearth as fast as said ore melts on said hearth, means including an ore hopper provided with a 95 supply of ore and connected to said plurality of ore chutes for feeding ore continuously to said hearth, a slag tap-hole at the combustion chamber end of said furnace, a matte tap-hole at the front or opposite end of said furnace from said combustion chamber, and door-controlled openings in the side of said furnace arranged to control said slag tap-hole. 100
18. In an automatic continuous ore feeding reverberatory smelting furnace, the combination with an operative fire box, of a combustion chamber, a wall inclosed ore 105 chamber connected at its back end to said fire box, an ore smelting hearth in the bottom of said chamber, a chimney in the front end portion of said ore chamber adapted to carry off the products of combustion flowing from said fire box into said ore chamber, an ore feeding chute extending through the wall of said ore chamber from its 110 top portion to the adjacent edge of the front end portion of said ore smelting hearth, and arranged and adapted to discharge ore continuously upon and onto and into said bed of molten ore upon said hearth, means including a 115 hopper connected to said ore chute and provided with a supply of ore for feeding ore continuously to said ore chute and said hearth, a tap-hole or holes at the back or fire box and hottest end portion of said ore chamber or hearth, arranged to draw off the slag element of said body 120 of molten ore, a tap-hole at the front and coolest end portion of said ore chamber and hearth adapted to draw off the matte element of said body of molten ore, and suitable doored openings into said ore chamber and hearth arranged to permit operative control of the smelting of said 125 ore in said ore chamber on said hearth and the slag entrances to said slag tap-holes.
- In testimony whereof I affix my signature in presence of two witnesses.
